(57) **CLAIM**

The ornamental design for an electrode bar for an optical fiber fusion splicer, as shown and described.

DESCRIPTION

FIG. 1 is a front view of an electrode bar for an optical fiber fusion splicer of the present invention.

FIG. 2 is a rear view of the electrode bar for an optical fiber fusion splicer of FIG. 1.

FIG. 3 is a top plan view of the electrode bar for an optical fiber fusion splicer of FIG. 1.

FIG. 4 is a bottom view of the electrode bar for an optical fiber fusion splicer of FIG. 1.

FIG. 5 is a right side view of the electrode bar for an optical fiber fusion splicer of FIG. 1.

FIG. 6 is a left side view of the electrode bar for an optical fiber fusion splicer of FIG. 1.

FIG. 7 is a perspective view from above of the electrode bar for an optical fiber fusion splicer of FIG. 1; and,

FIG. 8 is a rear perspective view from below of the electrode bar for an optical fiber fusion splicer of FIG. 1.

The broken line showing is for the purpose of illustrating environmental structure and forms no part of the claimed design.
